UNITED STATES PATENT OFFICE.

LEOPOLDO ROBERTO, OF PHILADELPHIA, PENNSYLVANIA.

GRAPHOPHONE.

1,414,898.

Specification of Letters Patent.

Patented May 2, 1922.

Application filed October 28, 1920. Serial No. 420,147.

To all whom it may concern:

Be it known that I, LEOPOLDO ROBERTO, a subject of the King of Italy, residing at Philadelphia, in the county of Philadelphia and State of Pennsylvania, have invented 5 certain new and useful Improvements in Graphophones, of which the following is a specification.

This invention relates to certain new and 10 useful improvements in graphophones, and has particular reference to the tone arm sound box mounting.

A further object of the invention resides in the provision of a graphophone wherein 15 the tone arm is freely detachable therefrom with the hinged cover of the graphophone box constituting a sounding board upon which the outlet end of the tone arm is supported.

20 A further object of the invention is to provide a tone arm for graphophones wherein the tone arm embodies a hinge connection intermediate the ends thereof to permit that portion of the tone arm supporting the 25 sound box to be moved upon its hinge connection to displace the sound box from the record disk.

A still further object of the invention embodies a novel adjustable mounting of a 30 sound box on a tone arm, the sound box being mounted in different angular relations relative to the tone arm to accommodate the stylus needle in traversing the playing grooves of a record disk of different formations.

35 With the above general objects in view and others that will appear as the nature of the invention is better understood, the same consists in the novel form, combination and 40 arrangement of parts hereinafter more fully described, shown in the accompanying drawings and claimed.

In the drawings, wherein like reference characters indicate corresponding parts 45 throughout the several views,

Figure 1 is a side elevational view of a 50 graphophone constructed in accordance with the present invention, a portion of the sectional tone arm and sound box being moved to inoperative position and illustrated by dotted lines,

Figure 2 is a top plan view of the same,

Figure 3 is a front elevational view of 55 the tone arm with the hinged section thereof elevated to inoperative position,

Figure 4 is a horizontal sectional view

taken on line IV—IV of Fig. 3 showing the rotatable connection between the tone arm and the supported bell end thereof,

Figure 5 is a cross sectional view taken 60 on line V—V of Fig. 1 showing the stylus arm of the sound box connected to the diaphragm;

Figure 6 is a front elevational view of the removable elbow of the tone arm for sup- 65 porting the sound box.

Figure 7 is a side elevational view of the removable elbow of the tone arm,

Figure 8 is a fragmentary side elevational view of the inner end of the tone arm showing 70 the hinge connection between the sections thereof, and

Figure 9 is a cross sectional view showing the connecting means between the elbow section and the hinged end of the tone arm. 75

Referring more in detail to the accompanying drawings and particularly to Figs. 1 and 2, there is illustrated a graphophone comprising a box 1 of hexagonal formation having a hinged cover 2 constituting a sound 80 board for the tone arm while the box 1 is provided with lifting handles 3 and an exteriorly positioned crank handle 4 for winding the motor mechanism contained within the box. A turn table 5 is supported upon 85 the platform 6 of the box and the speed of the motor mechanism is under control of the lever 7 as shown in Fig. 2 while the turn table 5 is maintained stationary by the brake lever 8. 90

The tone arm and sound box is shown in detail in Figs. 3 to 9 and includes a horn embodying sections 9 and 10, the section 9 being rotatably connected to the enlarged bell end 11 by a pin and slot connection 12 95 and 13 as shown in Figs. 3 and 4, the bell end carrying supporting pins 14 engaging in sockets 15 in the sound board cover 2 as shown in Figs. 1 and 3, the bell end 11 being mounted against rotation and permitting 100 limited rotary movement of the tone arm section 9 relative thereto.

The sections 9 and 10 of the tone arm are hingedly connected together as shown in Figs. 1 to 3 and 8, each section comprising a 105 hinged plate 16 pivoted together as at 17', the reduced open end of the section 9 being slightly enlarged to receive the adjacent projecting end 10' of the tone arm section 10, the hinged movement thereof being limited 110 by the peripheral flange 17 on the section 10 entering the collar 9' upon the section 9.

2

A removable elbow embodying an intermediate curved portion and right angularly extending ends is associated with the free end of the tone arm section 10 and to accommodate the connection therefor, the free end of the tone arm section 10 as shown in Figs. 3, 8 and 9 is provided with an annular flange 18 having the edge thereof provided with two pairs of relatively small and large recesses 19 and 20 and having relatively small perforations 19' diametrically opposite the small recesses 19 for purposes presently to appear. The removable elbow section is shown more clearly in Figs. 6 and 7 embodying a tubular member of equal diameter throughout and having an intermediate curved portion 21 with an angularly directed end 22 while the other end 23 thereof extends at right angles to the end 22. The outer side of the elbow section end 22 is provided with a lug 24 while a screw pin 25 having an operating head 26 is threaded transversely of the open end 22 with the head 26 of the screw adjacent the lug 24. In mounting the elbow section 21 upon the tone arm section 10, the end 22 of the elbow section enters the flange 18 of the tone arm section 10 with the lug 24 upon the elbow received in one of the large recesses 20 with the shank of the screw 25 received in a small recess 19 providing a clearance therefor, the end of the screw pin 25 opposite the head 26 adapted to engage in one of the perforations 19' when the said pin is rotated. In this position the screw 25 has the free end thereof extending through aligned openings in the end 22 of the elbow and through the flange 18 of the tone arm section 10, the lug 24 locking the elbow within the tone arm section 10 against rotary movement while the screw 25 securely retains the elbow within the tone arm.

The sound box shown in detail in Fig. 5 is preferably heart shape embodying a rear wall 27 carrying a collar 28 for reception upon the open end 23 of the elbow section 21 while a removable clamping plate 29 associated with the plate 27 clamps the diaphragm 30 within the sound box between the gaskets 31. A pair of brackets 32 is carried by the lower end of the clamping plate 29 and supports the cross arm 33 of the stylus bar 34, a set screw 35 being carried by the cross arm 33 for retaining a stylus needle 36 in position in the cross arm.

The screw pin and lug connection between the elbow section 21 and the tone arm permits the different angular mountings of the sound box upon the tone arm as shown

by full and dotted lines in Figs. 1 and 2, 60 the grooves of the record disk 37 being of various forms, some including vertical side walls and others tapering side walls so that the angular adjustment of the sound box as provided by this mounting will present the 65 stylus needle for proper playing position with records of various forms of grooves. When the sound box travels inwardly toward the center of the disk 37, the tone arm section 10 will rotate upon the bell mounting end 11 70 and at the playing end of the record the tone arm section 10 is moved upon its hinge connection 17 with the section 9 to elevate the sound box 27 from the disk 37. The elbow section 21 may be mounted upon the tone 75 arm section 10 to present major transverse axis of the sound box in parallel with the longitudinal axis of the tone arm, and by removing the screw 25 the elbow section 21 80 may be shifted relative to the tone arm section 10 to present the major transverse axis of the sound box at right angles to the longitudinal axis of the tone arm as shown by dotted lines in Fig. 2. The mounting flange 28 of the sound box is permitted a slight rotary movement on the end 23 of the elbow section to accommodate the sound box in encountering irregularities in the playing 85 grooves.

While there is herein shown and described 90 the preferred embodiment of the present invention, it is nevertheless to be understood that minor changes may be made therein without departing from the spirit and scope 95 of the invention as claimed.

What is claimed as new is:—

A tone arm for graphophones having a pair of relatively small and a pair of relatively large notches within the inner end of the tone arm and perforated at points diametrically opposite the small notches of the tone arm, an elbow section received in the inner end of the tone arm and having an integral lateral lug engaging in one of said relatively large recesses to prevent rotary 105 movement of the elbow in the tone arm, a transverse screw carried by the elbow, the portion of the screw between the elbow and its head being received in one of the small recesses of the said tone arm and the opposite end of said screw passing through the elbow and into one of the perforations of the tone arm to retain the elbow therein, and a sound box carried by the other end of the elbow.

In testimony whereof I affix my signature.

LEOPOLDO ROBERTO.
